W. DEURING.

GAGE.

APPLICATION FILED JUNE 17, 1918.

1,301,234.

Patented Apr. 22, 1919.

FIG. 3.

FIG. 2.

UNITED STATES PATENT OFFICE.

WILLIAM DEURING, OF CLEVELAND, OHIO.

GAGE.

1,301,234.

Specification of Letters Patent. Patented Apr. 22, 1919.

Application filed June 17, 1918. Serial No. 240,465.

To all whom it may concern:

Be it known that I, WILLIAM DEURING, a citizen of the United States, and a resident of Cleveland, in the county of Cuyahoga and 5 State of Ohio, have invented certain new and useful Improvements in Gages, of which the following is a specification.

This invention relates to gages used in carpentry, and an object of the invention is 10 to provide a gage adapted for use in mortising door frames and jambs for receiving hinge butts or leaves which gage is extremely simple in construction, durable and may be manufactured for a minimum cost, 15 comprising relatively few parts.

Another object of the invention is to provide a gage as specified, comprising a body formed of two right angularly disposed sections each of which carries at one end a right 20 angularly extending scribing point or wedge with which an adjustable abutment co-acts which abutments are adjustable along the outer faces of the right angular sections of the body to provide the proper space be- 25 tween the scribing wedge or point and the facing surface of the abutment, for regulating the width or depth of the mortise to be formed.

Other objects of the invention will appear 30 in the following detailed description, taken in connection with the accompanying drawing, forming a part of this specification, and in which drawing:

Figure 1 is a perspective view of the im- 35 proved tool.

Fig. 2 is a section on the line 2--2 of Fig. 1.

Fig. 3 is a longitudinal section through 40 one of the right angularly disposed sections of the gage.

Referring more particularly to the drawing, 1 designates the body of the tool as an 45 entirety which is formed of a single piece of sheet metal bent to form right angularly disposed sections 2 and 3. The sections 2 and 3 have extensions formed upon one of their ends, which extensions are bent at right angles to the sections and sharpened to form scribing wedges 4 and 5 respec- 50 tively. The scribing wedge 4 is formed upon the end of the section 2 oppositely from the end of the section 3 upon which the scribing wedge 5 is formed. Each of the sections 2 and 3 is provided with a longitudinally extending centrally disposed slot 6

which receives therethrough the screw 7 of a binding screw structure 8. The adjustable head 9 of each of the binding screw structures engages the inner surfaces of the sections 2 and 3 respectively while the rounded heads of the screws 7 engage against the outer surfaces of abutment members 10. The abutment members 10 are each formed of a single piece of sheet metal providing attaching portions 11 which lie in facial abutment with the outer surfaces of the sections 2 and 3, stay or guiding portions 12 which are formed upon the inner ends of the attaching portions 11 and are bent to extend over the corner of the body 1 and engage the section other than the one which is engaged by the attaching portion 11; for instance, the guiding portion 12 formed upon the end of the attaching portion 11 which abuts against the section 3 is bent at right angles to this attaching portion, extends over the corner of the body 1 and engages a portion of the surface of the section 2 adjacent the corner of the body. The abutment members 10 further comprise the outwardly extending portions 13 which face the scribing wedges 4 and 5 and co-act therewith in scribing a door casing or jamb to indicate the size of mortise or recess to be cut there- 75 in. If it is so desired, the body 1 may be provided with graduations as indicated at 14, along the corner thereof to facilitate a proper adjustment of the abutment members 10. 80

In use, one of the abutment members 10 is adjusted upon its corresponding section 90 of the body 1 to position it the proper distance from the scribing wedge or point carried by the said section to indicate one dimension of the mortise or cut-out portion 95 to be formed. After the abutment member has been properly adjusted, the binding nut 9 is adjusted upon the screw 7 to tightly clamp the abutment member in its adjusted position and the abutment member carried 100 by the other section of the body 1 may then be adjusted to position the portion 13 thereof the proper distance from the scribing wedge or point of this section to indicate a second dimension of the mortise or recess to 105 be cut, and thus these members may be maintained in their adjusted positions for marking or scribing several door jambs, frames or other articles to be worked upon, eliminating the necessity of adjusting, and re- 110

adjusting the abutment members to indicate the various dimensions, upon the scribing of a number of articles.

From the foregoing description, taken in connection with the accompanying drawing, it will be apparent that a carpenter's gage for use in scribing the mortises or recesses to receive hinge butts, or for scribing various other articles has been provided which is extremely simple in construction, and which may be conveniently and easily adjusted and operated.

Having fully described the invention, what is claimed is:

- 15 1. A gage comprising a body formed of sheet metal bent to form a pair of right angularly disposed sections and to form scribing edges at right angles to the body sections, and abutment members adjustably carried by said body sections.
- 20 2. A gage comprising a body portion formed of sheet metal bent to form a pair of right angularly disposed sections, extensions formed upon one end of each of said sections and bent at right angles thereto, said extensions being sharpened to form a scribing edge.
- 25 3. A gage comprising a body portion formed of sheet metal bent to form a pair of right angularly disposed sections, extensions formed upon the end of each of said sections and bent to project from the outer faces of the sections, said extensions being sharpened to form scribing edges, and abutment members adjustably carried by each of said body sections.
- 30 4. A gage comprising a body portion formed of sheet metal bent to form a pair

of right angularly disposed sections, extensions formed upon the end of each of said sections and bent to project from the outer faces of the sections, said extensions being sharpened to form scribing edges, abutment members adjustably carried by each of said body sections, guiding extensions formed upon said abutment members and bent to extend over the corner of said body and engage a portion of the surface of the body sections other than the body section which carries the respective abutment members. 50

5. A gage comprising a body formed of sheet metal bent to form a pair of right angularly disposed sections, an extension formed upon one end of each of said sections and bent to overhang the outer faces 55 of the sections, said extensions being sharpened to form scribing edges, abutment members adjustably carried by each of said sections, and including attaching portions, abutting portions extending at right angles 60 from one edge of said attaching portions, and guiding extensions formed upon the ends of said attaching portions and bent to extend over the corner of said body and engage a portion of the surface of the body 65 section other than the body section carrying the respective attaching portions.

6. A gage comprising a body including right angularly disposed sections, an angled scribing edge formed upon one end of each 70 of said sections, the scribing edge on one section being positioned on the end opposite the scribing edge-carrying end of the other section.

WILLIAM DEURING.
